CLAIM

The ornamental design for a display screen or portion thereof with animated graphical user interface as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of a first image of a display screen or portion thereof with animated graphical user interface;

FIG. 2 is a second image thereof;

FIG. 3 is a third image thereof;

FIG. 4 is a fourth image thereof; and,

FIG. 5 is a fifth image thereof.

The broken lines showing the remainder of the display screen or portion thereof with animated graphical user interface depict environmental structure and form no part of the claimed design. The appearance of the display screen or portion thereof with animated graphical user interface transitions between the images in the figures. The process or period in which one image transitions to another image forms no part of the claimed design.
